RUNNING REGISTER

Frank S. Shields, Jamaica, N. Y., assignor to
 S. & S. Corrugated Paper Machinery Co., Inc.,
 Brooklyn, N. Y., a corporation of New York

Application April 22, 1936, Serial No. 75,705

15 Claims. (Cl. 74—395)

This invention relates to registering mechanisms and more particularly relates to novel methods of and apparatus for angular and axial adjusting means for rotating members.

5 Machines which operate upon advancing sheet material, for example corrugated board, box blanks and the like, generally comprise a plurality of revolving members which perform successive operations upon the sheet. These machines are adjustable for different sizes of the product and the drums are approximately set into registering position while the machine is at rest. Accurate registration of the drums, particularly of the multi-color printing and the 10 15 slotting drums, is not feasible except after test runs upon the material are made.

To expedite the accurate angular and axial alignment of the successive drums, prior registering devices have been developed to perform the 20 adjustments while the machine was in operation in order to avoid starting up and stopping. An important advantage of running registering devices is that rapid compensation for speed changes and slippage of any particular drum or 25 of expansion or contraction of the product due to elasticity or other changes therein may be readily effected while the machine is maintained in operation.

The prior running registering devices included 30 clutches and manual hand adjusting operations which were necessarily slow and inconvenient. I contemplate a running register mechanism which dispenses entirely with clutch engagement or disengagement of the rotating drum and maintains a positive driving connection between the 35 rotating drum and its motive power. The vernier adjustments of my present invention are performed semi-automatically. The motive power for the drum is employed for effecting the vernier axial and angular drum adjustments.

This invention is in the nature of an improvement 40 of my co-pending application Serial No. 56,956, filed December 31, 1935, where the fundamental principles of the vernier angular and 45 axial adjusting means are disclosed. The vernier registration of the drums is preferably performed while the machine is running slowly so that the operator may readily determine the correct drum positions with a minimum of stock wastage. 50 However, if the initial registration should require re-adjustment, for example due to the higher normal speed of operation or due to slippage or the like, each drum is adjustable during any speed of its operation.

55 The elimination of clutch connections between

the motive power and the rotatable drum is accomplished in my present invention by surrounding the registering mechanism with a sleeve which is connected to the internal mechanism which connects to the drum shaft by a worm gear arrangement to complete the positive driving connection from the drum shaft and the motive power. Angular displacement of the drum shaft with respect to the external sleeve is effected by rotation of the worm in a manner 5 to be described in detail. 10

Slotter heads are generally adjusted axially before the machine is started up and circumferential adjustment alone is usually necessary during operation. My present invention is applicable to angular registration without the axial 15 adjustments and accordingly I disclose herein-after a preferred embodiment of such an application.

It is accordingly an object of my present invention to provide novel methods of and apparatus for running registration of rotating drums. 20

Another object of this invention is to provide a novel running register which maintains a positive driving connection between the motive power 25 and the rotatable drum.

A further object of this invention is to provide a novel semi-automatic running register for optional angular or axial drum adjustment. 30

Still a further object of this invention is to provide a novel semi-automatic running register for angular adjustment. 35

Other objects of my invention will be evident in the following description taken in connection with the drawings, in which:

Figure 1 shows an elevation of the register mechanism. 35

Figure 2 is a cross-sectional illustration of the register mechanism.

Figure 3 is the cross-sectional view taken along 40 3—3 of Figure 2 of the angular adjusting mechanism in neutral position.

Figure 4 shows an off-neutral position of Figure 3. 45

Figure 5 is the cross-sectional view taken along 5—5 of Figure 2 of the gear shifting mechanism.

Figure 6 is the cross-sectional view taken along 6—6 of Figure 2 of the register drive control mechanism.

Figure 7 is the sectional view taken along 7—7 50 of Figure 1 of the register control mechanism.

Figure 8 is an end view taken at 8—8 of Figure 1.

Figure 9 is a partial perspective view of the vernier angular adjusting mechanism. 55

Figure 10 is a partial sectional view of a modification of my present invention as applied to a slotter drum where only angular registration is required.

- 5 Figure 11 is the corresponding modification of the register drive for the embodiment of Figure 10.

In applying my present invention to printer drums and the like, where both angular and axial 10 adjustments are required, the preferred modification illustrated in connection with Figures 1 to 9 is disclosed to particularly set forth the invention. Referring to Figure 1, 10 represents the printer drum or rotating member which requires the axial 15 and angular adjustment for accurate registration upon a moving sheet or stock between the drum 10 and presser roller 11.

Drum 10 is normally rotated by motive power impressed upon gear 12 which is secured to shaft 20 13. Shaft 13 is supported on frame members 14 and 15 housing roller bearings 16 and 17 respectively (Figure 2). Gear 12 engages gear 18 which is bolted to sleeve 20. The shaft 21 of drum 10 is normally rotated by the motivation of 25 gear 18 and sleeve 20 as will be described in detail hereinafter. The mechanism housed within sleeve 20 provides the registry adjustments in accordance with the present invention which adjustments normally rotate as a unit with sleeve 20.

30 A further sleeve 22 is secured to sleeve member 23 within sleeve 20 by screws 24, and is rotated therewith. Spur gear 25 is integral with sleeve 22 and engages with gear 26 to normally continuously rotate a friction cone 27. Friction cone 27 35 supplies the power for motivating the axial and angular drum adjustments under the control of hand wheel 28 as will be described hereinafter. Extension bracket 30 from frame member 31 supports the friction drive mechanism co-acting with 40 friction cone 27 and bracket 32. A guard 33 is attached to the outside end of bracket 32 for housing the changeover mechanism which the operator controls by hand lever 74 to effect either the axial or angular drum alignment.

45 In accordance with this invention, the full angular or 360° control of drum 10 is divided into two operations. The first operation resolves itself into a manual adjustment of the drum 10 to the approximate registry position while drum 10 is 50 at rest. It is a simple matter for the operator to approximate the drum registry for example within ten degrees of the drum angle. The second operation is the semi-automatic vernier adjustment of the drum while rotating for precise angular 55 registration.

The axial adjustment of drum 10 is independently accomplished while the drum is in rotation. It is preferable to perform the longitudinal and the final axial adjustments while the machine is operating at a relatively slow speed in order to prevent undue wastage of stock until accurate adjustment is achieved and in order to more readily effect the adjustments. However, realignment of the drum while the machine is in 60 operation is preferable at the normal operating speed.

70 The approximate angular adjustment of drum 10 is accomplished by operation upon the square head 35 with a hand wrench while drum 10 is at rest. The rotation of the square head 35 correspondingly rotates the worm 36 (Figure 3) which engages with worm gear 37 set into sleeve 23. As more clearly represented in cross-sectional view Figure 2, shaft 21 of drum 10 is rotatably 75 linked with sleeve 23 in the following manner:

Extension 21a of shaft 21 contains a key 40 engageable with the extended keyway 41 in sleeve 42. Sleeve 42 supports the spur gear or pinion 43 on the threaded shaft or screw member 44.

Figure 9 is a perspective illustration of the end 5 portion of sleeve 42 supporting gear 43 on threaded shaft 44 in bosses 45—46. Sleeve 23 surrounds sleeve 42 and contains the worm gear teeth 37. At the end portion of sleeve 23 corresponding to the position of spur gear 43 is contained members 47 containing stop plates 48 for abutting the corresponding ends 49—50 of shaft 44.

By rotating worm 36 at its square head 35 the intermediate sleeve 23 is revolved angularly with 15 respect to the outer sleeve 20. Members 48 mounted in sleeve 23 abut ends 50 of shaft 44 rotating sleeve 42 therewith. Sleeve 42 is carried along with the rotation of sleeve 23 so that the same angular displacement between intermediate 20 sleeves 23 and outer sleeves 20 is accomplished. Since sleeve 42 contains keyway 41, shaft 21 will be correspondingly angularly displaced with respect to housing sleeve 20 as will now be understood. 25

Angular adjustment of drum 10 is accordingly feasible over 360° of rotation, adjustable in a clockwise or counterclockwise sense in accordance with the rotation of worm 36. It is to be understood that the manual adjustment of drum 10 by 30 means of a hand wrench rotation of worm 36 is performed while driving gear 12 is at rest. Drum 10 is approximately adjusted into angular registration in this manner, and a positive drive connection is maintained between the drive gear 12 35 and drum 10.

Precise angular registration is accomplished semi-automatically. The principle of the vernier adjusting mechanism of the present invention is disclosed in my co-pending application Ser. No. 40 56,956 referred to above. As will be hereinafter described in detail, an axial motion is imparted to rack member 51 in proportion to the required final angular adjustment. The transverse motion of member 51 is accomplished while drum 10 45 is running by the motive connection of driving gear 12 and gear 18. The rotation of gear 18 carries therewith housing sleeve 20 which contains the worm 36 in turn meshing with worm gear 37 so that sleeve 23 is normally rotated therewith, in turn rotating shaft 21 in the manner already described. Transverse movements of rack member 51 will perform corresponding small angular displacements of sleeve 42 with respect to sleeve 23 to correspondingly angularly displace 50 revolving drum 10 forwardly or rearwardly with respect to the driving gear members 12 and 18. 55

As described in my co-pending application already referred to, the relative angular displacement due to the transverse motion of rack member 51 is accomplished in the following manner: Rack member 51 encloses shaft 52 which is connected to extension shaft 21a by pin 53. Figure 9 is a perspective illustration of the gear member 43 and rack member 51 in sleeve 42. Rack teeth 65 54 of rack member 51 engage gear 43 so that an axial movement of rack member 51 will correspondingly rotate the gear 43 clockwise or counter-clockwise. The upper half of Figure 3 is a cross-sectional illustration through the angular 70 displacing mechanism comprising gear 43. Gear 43 is internally threaded with teeth 55 to mesh threads 56 of screw member 44. Since gear 43 is restrained from axial movement by bosses 45—46, the screw member 44 will be forced to 75

move axially in accordance with the rotation of gear 43. Rotation of screw member 44 is prevented by key 38 fixed in bosses 45—46 and keyway 39 in the member 44.

5 Ends 49 and 50 of screw member 44 are rounded to permit a sliding movement with respect to plates 48. If the rotation of gear 43 (actuated by rack member 51) moves screw member 44 towards the left, the end 49 will abut plate 48 and force its supporting mechanism to the position illustrated in Figure 4. Figure 4 shows about a ten degree angular shift of screw member 44.

10 Sleeve 42, which supports screw member 44 and gear 43 is correspondingly angularly displaced with respect to sleeve 23 (which contains plates 48). Shaft 21 will accordingly be angularly displaced since it is keyed thereto by keys 40. It is to be understood that this angular displacement of drum 10 with respect to gears 12 and 13 is accomplished in its running condition. A ten degree adjustment in either direction from neutral may readily be made using this "reaction" principle. Precise split-hair angular registry of drum 10 is performed by operation of rack member 51.

15 Power for the axial movement of rack member 51 is transmitted from revolving friction cone 27 as follows: As already described, friction cone 27 is normally rotated by gear 26 meshing with gear 30 25 (Figures 1 and 2). A stud 57 mounted in extension 58 of bracket 33 rotatably supports friction cone 27. Co-actable friction disks 60 and 61 are independently engaged with gear 27 to rotate their common shaft 62 to which they are pinned in either direction (Figures 6 and 7).

20 Shaft 62 is supported in yoke 63 extending from bracket 30 attached to the frame. An externally threaded sleeve 29 co-acts with the internally threaded sleeve 59 set in one end of yoke 63. Shaft 62 is rotatable within sleeve 29. Hand wheel 28 is connected to sleeve 29 by set screw 28'. The set screw 28' projects into an annular groove 62' on shaft 62 so that shaft 62 is free to rotate with respect to hand wheel 28 and sleeve 29 but is constrained to move axially therewith. Roller thrust bearings 70—70' are attached to either end of sleeve 29. A nut 64 is pinned to shaft 62. Worm 65 is slidably keyed to the opposite end of shaft 62 by key 66. Roller thrust bearings 70'—70' are attached to the opposite ends of worm 65.

25 Optional engagement of friction disks 60 and 61 with friction gear 27 is effected by suitable rotation of hand wheel 28 as will now be evident. Rotation of hand wheel 28 will correspondingly move sleeve 29 outwardly or inwardly to engage disks 60 or 61 respectively. Clockwise or counterclockwise rotation of shaft 62 will correspondingly rotate worm 67 which is connected to shaft 68 by pin 69. This arrangement of the driving attachment of the shaft 68 to the friction gear 27 is accomplished by the operation of hand wheel 28. Hand wheel 28 is not rotated since shaft 62 is free to rotate within the sleeve 29.

30 Shaft 68 is accordingly motivated from cone 27 in either sense according to the optional engagement by hand wheel 28. Spur gear 71 is slidably keyed to shaft 68 and rotates therewith. Spur gear 71 is alternatively engageable with gear 72 or gear 73 according to the position of the three-position lever 74. As will be described herein-after, gear 72 corresponds to the angular registration of drum 10 and gear 73 corresponds to the axial registration of drum 10. The engagement

of spur gear 71 with gear 72 or 73 is accomplished as follows:

35 Referring to Figures 5 and 8, lever 74 is attached to rod 75, the opposite end of which is connected to yoke 76. A pin 77 projects from lever 74 from a contained spring 78 to rest in corresponding detents in bracket arm 80. Three detents corresponding to neutral angular and axial engagement of gear 71 for effecting corresponding drum 10 registration are set in the bracket 10 arm 80. Arms 81—81 of yoke 76 engage hub 82 of gear 71 as illustrated in Figure 7. Engagement of gear 71 with either gear 72 or gear 73 is accomplished by merely shifting lever 74 to the proper position, preferably when friction cone 27 15 is not engaged. For angular adjustment of drum 10, gears 71 and 72 are engaged.

20 Referring to Figure 2, the hub 83 of gear 72 is threaded to engage threaded member 84. Gear 72 is constrained from axial movement by projection 85 of housing 33 in its hub 83. Threaded member 84 is slidably keyed to sleeve 86 by key 87. Rotation of gear 72 accordingly forces threaded member 84 into axial movement. End portion 88 of threaded member 84 is connected 25 thereto by semi-circular extension 89. Extension 89 is slidably keyed to bracket 32 by key 90 as illustrated in Figures 2 and 6, to restrain threaded member 84 from angular movement.

25 Axial displacement of member 84 due to rotation of gear 72 accordingly carries end portion 88 axially. Inner race of ball bearing 91 is attached to member 88. Ball bearing 91 is set into extension hub 92 of rack member 51 (Figure 2). It is to be understood that member 88 is free to move axially with respect to shaft 52 and bracket 32; and rack member 51, with respect to shaft 52.

30 Transverse movement of rack member 51 is accordingly effected by rotation of gear 72 as 40 will now be understood. When lever 74 is moved to engage gear 71 with gear 72, drum 10 is ready for precise angular registration. Moving hand wheel 28 outwardly or inwardly will cause corresponding disks 60 or 61 to engage with revolving 45 friction cone 27, to correspondingly move rack member 51 axially. Gear 43 is accordingly rotated to perform the angular adjustment of drum 10 in a manner hereinabove described in a clockwise or counterclockwise sense.

35 Axial registration of drum 10 is accomplished by engaging gear 71 with gear 73 by simply moving lever 74 while friction gear 27 is disengaged. Hub 93 of gear 71 is internally threaded to engage with the finely threaded sleeve 86. The pitch of threads 94 of sleeve 86 is small to permit vernier axial adjustment of drum 10. Flange 95 is bolted to gear 73 and is set into hub 93 of gear 72 to prevent axial movement of gear 73. When gear 73 rotates, sleeve 86 must accordingly 60 move axially with respect to gear 73. A ball bearing 96 connects the end of sleeve 94 with an extension 97 of shaft 52. Shaft 52 is accordingly free to rotate with respect to sleeve 86 which carries shaft 52 axially along with it. Axial 65 movement of sleeve 86 resulting from the rotation of gear 73 accordingly moves shaft 52 therewith to correspondingly move the shaft 21 of drum 10, the end 21a of which is pinned to shaft 52. It is to be understood that the axial adjustment of drum 10 may be made in either direction according to the engagement of cone 27 with either disk 60 or 61; and that this adjustment is effected when the drum is in rotation.

70 The accurate angular and axial adjustment of 75

drum 10 may be "locked" by turning the thumbscrews 98 and 99 respectively (Fig. 1). Thumbscrews 98 and 99 operate corresponding plates 100. As illustrated in Figure 5, plate 100 abuts 5 the surface of gear 72 when the rod 101 to which it is riveted, is moved downwards by thumb-screw 98 turning on the threaded portion 102. Plate 100 is guided by pins 103. Other well known adjustment locking means may be used to maintain 10 the vernier adjustments of drum 10.

When re-alignment of drum 10 is necessary due to speed change or slippage, or due to the stock itself, the plates 100 are released from gears 72 and/or 73 to permit operation of the vernier 15 angular and/or axial registering mechanism.

The running register is also applicable to a revolving drum requiring only angular adjustment. For example, a slotted head is adjusted axially on its shaft while the machine is at rest and it is 20 only necessary to perform angular registration while the machine is in operation. In Figures 10 and 11, I illustrate a modification of my present invention as applied to a slotted head requiring only angular registration adjustments.

25 Figure 10 is a partial cross-sectional illustration corresponding to the Figure 2 of the first described embodiment. Since axial adjustments are not required, the rod 52 extending from the shaft 21a through the vernier adjusting mechanisms is not required. 21'a corresponds to the shaft 21a of Figure 2 and is slidably keyed to sleeve 42a by key 40a in keyway 41a. Sleeve 42a supports the screw member 44a and the gear 43a in a manner hereinabove described in connection 30 with the similarly numeralled members without the added letter "a" of the former angular and axial embodiment. Rack member 54a coacts with gear 43a to effect the vernier angular registration of the drum (not shown) attached to 35 the shaft 21a.

40 For simplification in the presentation of the modification in connection with Figures 10 and 11, I have labelled the members of these views which correspond to members in the modification described in connection with Figures 1 to 9 with the same numerals and an additional letter "a". The approximate angular adjustment performed while the drum is at rest, circumferentially adjustable over 360° is effected by an operation of the 45 worm 36a supported in a housing sleeve 20a which coacts with the worm gear 37a of sleeve 23a in a manner already described.

45 The vernier angular adjustment is accomplished by transversely motivating rack member 54a semi-automatically. Friction cone 27a is supported on bracket 63a of extension bracket 30a. Spur gear 26a is attached to friction cone 27a and is driven by the co-acting gear 25a integral with sleeve member 22a bolted to sleeve 23a. 50 Gear 25a is rotated through the rotation of the drum and corresponding sleeve members, as is understood.

55 Friction cone 27a is optionally engageable with either friction disk 60a or 61a (Figure 11) by operation of hand wheel 28a in a manner already described in connection with Figures 6 and 7 to effect a clockwise or counterclockwise rotation of their common shaft 62a. The rotation of shaft 62a correspondingly revolves shaft 68a 60 which is keyed to the gear 71a. Gear 71a engages with the gear 72a to effect the axial movement of rack member 54a in a manner to be described in detail.

65 The structural difference between the modification of Figures 10 and 11 and the other em-

bodiment resides in a permanent engagement of gears 71a and 72a and the elimination of the changeover lever 74 as will now be evident. The semi-automatic operation of the vernier registration is effected in a clockwise or counterclockwise 5 sense by suitable operation of hand wheel 28a.

Referring now to Figure 10, the hub 83a of gear 72a is internally threaded and engages with the externally threaded shaft 84a. Shaft 84a corresponds to the threaded member 84 shown in 10 Figure 2 and is not hollow since no axial adjusting shaft for the drum is required. In a similar manner, rack member 54a is also not hollow. The end portion 88a of threaded shaft 84a is attached to the extension 92a of rack member 54a 15 by a roller bearing 91a. The inner racer of roller bearing 91a is secured to the shaft extension 88a by nut 105. The outer racer of bearing 91a is secured to extension 92a by nut 106.

20 Threaded shaft 84a is slidably keyed to bearing 32a by key 90a. Shaft 84a is accordingly constrained to move only axially and roller bearing 91a permits the normal rotation of rack member 54a within sleeve 22a. The transverse or axial motivation of rack member 84 is effected 25 by suitable rotation of gear 72a through the coaxing gear 71a as driven from the friction cone 27a. The hub 83a of gear 72a has an annular groove retaining the collar 85a and is accordingly restrained to rotate and is not movable 30 axially. Rotation of gear 27a accordingly forces screw member 84a to the right or left according to the sense of its rotation. Axial movement of shaft 84a correspondingly moves rack member 54a to rotate the gear 43a which in turn effects the 35 vernier angular adjustment of the drum member in a manner described in detail in connection with Figures 3, 4 and 9.

40 It is to be understood that my present invention may be applied to each of the several successive drums operating upon a sheet advancing through the machine to provide an independent registering mechanism for the respective drums. Printer drums are preferably provided with the angular and axial adjusting register 45 described in connection with Figures 1 to 9 whereas slotted drums need only be provided with the angular register described in connection with Figures 10 and 11. The preliminary approximate angular adjustment of each drum is made while 50 the machine is at rest. The slotted heads are then adjusted axially. The vernier angular and/or axial adjustments of the respective drums are made while the machine is running, preferably at a slow rate so that the operator may readily perform the necessary adjustments with a minimum stock wastage. The vernier adjustments are then "locked" into position. Should re-adjustment 55 of any particular drum be necessary in the normal operation of the machine such adjustment 60 may be effected at the normal speed, if desired.

65 Although I have illustrated particular embodiments of my present invention, it will be evident to those skilled in the art that modifications may be made which fall within the broader spirit and scope thereof and accordingly I do not intend to be limited except as set forth in the following claims.

I claim:

70 1. In a running register, a drum; a source of motive power for driving said drum; a positive drive connection from said source of motive power to said drum; means for angularly displacing said drum with respect to said motive power for obtaining 75 adjustments therebetween through 360

degrees; and vernier adjusting means for angularly displacing said drum with respect to said motive power; said first and second means being operative while maintaining said positive drive connection from said source of motive power to said drum.

2. In a running register, a drum; a source of motive power for driving said drum; a positive drive connection from said source of motive power to said drum; means for angularly displacing said drum with respect to said motive power for obtaining adjustments therebetween through 360 degrees; and vernier adjusting means for angularly displacing said drum with respect to said motive power while said drum is in rotation; said first and second means being operative while maintaining said positive drive connection from said source of motive power to said drum.

3. In a running register, a drum; a source of motive power for driving said drum; a positive drive connection from said source of motive power to said drum; means for angularly displacing said drum with respect to said motive power for obtaining adjustments therebetween through 360 degrees; vernier adjusting means for angularly displacing said drum with respect to said motive power while said drum is in rotation; said first and second means being operative while maintaining said positive drive connection from said source of motive power to said drum; and a second vernier adjusting means for axially displacing said drum while said drum is in rotation.

4. In a running register, a drum; a source of motive power; a positive drive connection from said source of motive power to said drum; said drive connection including a worm and worm gear connection; said worm being rotatable to angularly displace said worm gear with respect to said worm; and said positive drive connection further including a vernier angular adjusting means operable while said drum is in rotation.

5. In a running register, a drum; a source of motive power; a drive connection from said source of motive power to said drum; means operative from said source of power for angularly displacing said drum with respect to said motive power; means operative from said source of power for axially adjusting said drum; and means connected in the drive connection from said source of motive power to said adjusting means for determining the sense of said adjustments and means for selectively applying said source of motive power to said angular and axial adjusting means.

6. A running register for a rotatable member secured to a driven shaft arranged to be rotated by a drive gear through a positive driving connection comprising: a first sleeve; a driven gear secured to said sleeve for operative connection with said drive gear; a second sleeve, concentric with said first sleeve; means for angularly displacing said rotatable member with respect to said drive gear for substantially 360 degrees; vernier adjusting means for angularly displacing said member with respect to said drive gear, including a third sleeve concentric with said second sleeve containing mechanism for angularly displacing said third sleeve with respect to said second sleeve in either sense, said third sleeve being keyed to said driven shaft; and apparatus for operating said mechanism.

7. A running register for a rotatable member secured to a driven shaft arranged to be rotated by a drive gear through a positive driving connection comprising: a first sleeve; a driven gear secured to said sleeve for operative connection

with said drive gear; a second sleeve, concentric with said first sleeve; means for angularly displacing said rotatable member with respect to said drive gear for substantially 360 degrees; vernier adjusting means for angularly displacing said member with respect to said drive gear, including a third sleeve concentric with said second sleeve containing mechanism for angularly displacing said third sleeve with respect to said second sleeve in either sense, said third sleeve being keyed to said driven shaft; and apparatus for operating said mechanism including an axially displaceable element and structure operative from the rotative power of said drive gear for selectively moving said element in either direction to effect a corresponding angular displacement between said second and third sleeves.

8. A running register for a rotatable member secured to a driven shaft arranged to be rotated by a drive gear through a positive driving connection comprising: a first sleeve; a driven gear secured to said sleeve for operative connection with said drive gear; a second sleeve, concentric with said first sleeve; means for angularly displacing said rotatable member with respect to said drive gear for substantially 360 degrees; vernier adjusting means for angularly displacing said member with respect to said drive gear, including a third sleeve concentric with said second sleeve containing mechanism for angularly displacing said third sleeve with respect to said second sleeve in either sense, said third sleeve being keyed to said driven shaft; and apparatus for operating said mechanism including an axially displaceable element and structure operative from the rotative power of said drive gear for selectively moving said element in either direction to effect a corresponding angular displacement between said second and third sleeves; said structure comprising an internally threaded sleeve cooperative with a threaded portion of said element and secured against axial displacement.

9. A running register for a rotatable member secured to a driven shaft arranged to be rotated by a drive gear through a positive driving connection comprising: a first sleeve; a driven gear secured to said sleeve for operative connection with said drive gear; a second sleeve, concentric with said first sleeve; means for angularly displacing said rotatable member with respect to said drive gear for substantially 360 degrees; vernier adjusting means for angularly displacing said member with respect to said drive gear, including a third sleeve concentric with said second sleeve containing mechanism for angularly displacing said third sleeve with respect to said second sleeve in either sense, said third sleeve being keyed to said driven shaft; and apparatus for operating said mechanism including an axially displaceable element and structure operative from the rotative power of said drive gear for selectively moving said element in either direction to effect a corresponding angular displacement between said second and third sleeves; said structure comprising an internally threaded sleeve cooperative with a threaded portion of said element and secured against axial displacement, and a clutch for connecting said threaded sleeve to said rotative power for rotating said threaded sleeve in either sense to correspondingly axially displace said element for effecting the vernier angular adjustment of said rotatable member.

10. A running register for a rotatable member secured to a driven shaft arranged to be rotated by a drive gear through a positive driving

spect to said drive gear including a third sleeve concentric within said second sleeve containing mechanism for angularly displacing said third sleeve with respect to said second sleeve in either 5 sense, said third sleeve being keyed to said driven shaft; apparatus for operating said mechanism including an axially displaceable element and structure for selectively moving said element in either direction to effect a corresponding angular 10 displacement between said second and third sleeves; said structure comprising threaded sleeve cooperative with a threaded portion of said element and secured against axial displacement, and a clutch for connecting said threaded sleeve to 15 said rotative power for rotating said threaded sleeve in either sense to correspondingly axially displace said element for effecting the vernier angular adjustment of said rotatable member; and means operative by said clutch for axially 20 displacing said rotatable member comprising a rod connected to said driven shaft and extending axially through said element, an externally threaded sleeve rotatably secured to said rod, and a second threaded sleeve secured against 25 axial displacement driveable by said clutch in either sense for correspondingly axially displacing said rod and said member.

15. A running register for a rotatable member secured to a driven shaft arranged to be rotated by a drive gear comprising: a first sleeve; a driven gear secured to said sleeve for operative connection with said drive gear; a second sleeve concentric within said first sleeve; means for angularly displacing said rotatable member with respect to said drive including a worm gear integral with said second sleeve and a worm engaging with 30

said worm gear and rotatably secured in said first sleeve; vernier adjusting means for angularly displacing said member with respect to said drive gear including a third sleeve concentric within said second sleeve containing mechanism for angularly displacing said third sleeve with respect to said second sleeve in either sense, said third sleeve being keyed to said driven shaft; apparatus for operating said mechanism including an axially displaceable element and structure for selectively moving said element in either direction to effect a corresponding angular displacement between said second and third sleeves; said structure comprising threaded sleeve cooperative with a threaded portion of said element and secured against axial displacement, and a clutch for connecting said threaded sleeve to said rotative power for rotating said threaded sleeve in either sense to correspondingly axially displace said element for effecting the vernier angular adjustment of said rotatable member; and means operative by said clutch for axially displacing said rotatable member comprising a rod connected to said driven shaft and extending axially through said element, an externally threaded sleeve rotatably secured to said rod, and a second threaded sleeve secured against axial displacement driveable by said clutch in either sense for correspondingly axially displacing said rod and said member; and means for selectively connecting said first or second internally threaded sleeve to said clutch for correspondingly effecting the vernier angular or axial registration of said rotatable member while in rotation.
